(57) **CLAIM**

The ornamental design for a digital video recorder for monitoring cameras, as shown and described.

DESCRIPTION

FIG. 1 is a top, front and left side perspective view of a digital video recorder for monitoring cameras showing my new design,

FIG. 2 is a front elevational view thereof,

FIG. 3 is a top plan view thereof,

FIG. 4 is a right side elevational view thereof, a left side elevational view being mirror image

FIG. 5 is a rear elevational view thereof,

FIG. 6 is a bottom plan view thereof,

FIG. 7 is a top, front and left side perspective view of a second embodiment of a digital video recorder for monitoring cameras showing my new design,

FIG. 8 is a front elevational view thereof,

FIG. 9 is a top plan view thereof,

FIG. 10 is a right side elevational view thereof, a left side elevational view being mirror image

FIG. 11 is a rear elevational view thereof; and,

FIG. 12 is a bottom plan view thereof.
